GOLF CLUB

Milton B. Reach, Springfield, Mass.

Application February 13, 1942, Serial No. 430,811

22 Claims. (Cl. 273—80)

This invention relates to golf clubs and has divers objectives as will be set forth herein. In its broad principles of assembly the invention relates to both "wood" and "iron" type clubs.

Iron clubs have almost exclusively been made in what may be described as the external hosel type, wherein the hosel of the head is a socket into which is assembled the shaft. This assembly is of several common forms. In one form the shaft and hosel are threaded together; in another they are riveted together; in another they are united in a frictional contact. In all of these assemblies a shoulder results at the top of the hosel member that is usually finished off by tapered wrappings or by a ferrule. The common practice therefore is to assemble the parts into a semi-finished club and thereafter complete the finishing operations. In "wood" clubs the "socket" of the head is bored to receive the end of the shaft (which is usually pinned in), and the shaft is assembled thereto with the head in the "white." The parts are then blended together in a sanding operation, wrappings applied, and finally finished.

It will be noted in these various assemblies no flexibility of procedure or assembly exists in the shipping room. Clubs are started and finished to a prescribed model or specification, and undesirable stock accumulations result—particularly as most manufacture is made ahead of season and models, weights, lengths, etc., must be guessed at and guided by historical records.

Broadly, I seek to correct some of these handicaps of manufacture—restyle the golf line and introduce meritorious playing features.

It is an object of my invention that shafts of various styles and makes can be stored in their full finish. Also golf club heads of various shapes and weights can be stored in their full finish, and the parts can be mated together to meet the requirements of current orders in the assembly shipping room. This contributes to efficiency in service and decreased stock investment. To this end, the invention contemplates the provision of a construction of golf club enabling ready and secure assembly of the shaft to the hosel of the club head.

I accomplish my purposes as hereinafter described by way of example.

In the accompanying drawings

Figure 1 is a view partly in longitudinal section, and partly in elevation of a club head of the iron type with a portion of the shaft.

Fig. 2 is a cross sectional view of the upper part of the hosel on the line 2—2 of Fig. 1.

Fig. 3 is a cross sectional view of the lower end

of the tubular metal shaft on the line 3—3 of Fig. 1.

Fig. 4 is a view similar to Fig. 1 of a modified form of club of the "iron" type.

5 Fig. 5 is a cross section of a part of the hosel of Fig. 4 on the line 5—5. Fig. 5a is a cross sectional view of head of the screw forming a part of the hosel of Fig. 4, on the line 5a—5a.

Fig. 6 is a cross sectional view of the hollow metallic shaft on the line 6—6 of Fig. 4.

Fig. 7 shows the club head and hosel of Fig. 4 partly in section.

Fig. 8 is a sectional view of the hosel head of Fig. 4.

15 Fig. 9 shows a wooden head combined with an internal hosel of metal.

Referring to Figs. 1 to 3 inclusive the club head

17 of the iron has an internal hosel 8, or one that fits into a hollow shaft. This hosel is in one piece integral with said club head. It has a stem portion 9 of reduced diameter relative to the diameter of its head portion 10 and to the body or base portion 8 which is of the same diameter as the hosel head.

20 25 This structure of the internal hosel with portions of relatively different diameters enables me to obtain a tight and proper fit between the parts, hosel and hollow metallic shaft, because the differential diameters present shoulders extending circumferentially of the hosel with which complementary annularly arranged shoulders on the interior of the shaft will contact to make a tight joint as will appear hereinafter.

The head 10 of the internal hosel is provided with keyways or grooves 10a say for instance, two in number spaced 180°, or three in number spaced 120° apart, as shown. These keyways are comparatively shallow and they communicate with the annular space 9a around the stem 9 of the hosel, so that shoulders are provided at 11 at the lower ends of said keyways which are engaged by a shoulder on the interior of the shaft. The keyways are preferably of less depth than said space.

40 45 The lower end of the hollow metal shaft is provided with keys 12 pressed inwardly of the thin metal composing the shaft. These rib like portions are desirably located 120° apart. They are adapted to pass through the keyways or grooves

50 55 10a when the shaft is being assembled by forcing it axially into place on the hosel so that by then turning the shaft relative to the hosel the shoulders at the upper ends of the keys will be moved to positions out of line with the keyways 10a and will engage the underside of the shoulder 11 of

the head 10 of the hosel and thus the shaft will be locked to the hosel against being withdrawn by a movement in an axial direction.

The head 10 of the internal hosel may be integral, as shown, with the stem portion 9 of said hosel or it may be riveted thereto or attached by a screw thread. The larger diameters are approximately of a size to permit a slip fit for the shaft.

Before the hollow shaft is placed on the hosel a slug R of suitable binding material is placed within the shaft at its lower end portion, said material being of a kind to fasten the shaft and hosel together. This material may be rubber, or plastic or a low melting babbitt metal (or the like). The volume of this binding material composing the slug would depend upon the amount of space that is to be filled within the joint between the hosel and the shaft. The different assemblies i. e. whether using rubber, plastic or low melting metal produce different qualities of feel. Rubber is the most suitable material for "sweetness" and shock absorbing qualities as well as having the capacity of recovery from torsional actions.

Having placed the slug of binding material (or material having other characteristics) in position as indicated at R, I then thrust the shaft onto the hosel as far as it will go and then with a quarter turn lock the shaft against the hosel. Then the portion of the club where the slug is located is clamped in a heating unit and a pressure mandrel is introduced into the hollow shaft from the upper end thereof and sufficient heat is applied to melt the slug of material, whereupon the material will be forced downward by the pressure mandrel into all the open spaces between the shouldered hosel and shaft, thereby securely locking the parts into a perfect union.

When rubber is used as the filling and binding material I first apply to the metal parts a material to bond rubber and steel in a vulcanized union. This rubber will give a cushioning effect both laterally and circumferentially of the parts and the rubber will react to restore the parts to normal position. In a plastic assembly a plastic material may be used in liquid form and solidified under heat after being introduced to the spaces within the joint. Some materials could be melted and "set" in a hot water bath and thereafter cooled. I do not limit myself to any particular method, the desired result being possible of achievement by various means, known to those skilled in the art but whatever means or method is employed the filling material when set will hold the parts in the position, substantially as assumed by them when they are interlocked by giving a relative movement of a quarter turn of one member in respect to the other.

It will be noticed that I overcome objections and difficulties in obtaining a tight and proper fit between the parts by carrying out the formation of the joint between the shaft and hosel by employing as a feature of said joint the two or more differential diameters of the parts to initially provide an interlocking connection by rotating one member, say a quarter turn relative to the other, and then applying to the assembled elements the cushioning or filling material which by occupying all spaces within the joint compensates for any lack of tightness in the initial fit of parts, and secures the parts together in their assembled relation.

The keys 12 are desirably provided by pressing them inwardly from the sheet metal shell of which

the shaft is composed. These keys are desirably of elongated or rib like form, although the invention is not limited in this respect. These rib like members or projections may be formed by a blunt pointed tool and they may be of generally arc shape or of other cross sectional shape. They are made of a width to slide through the keyways into a position to interlock with the shoulders on the hosel when the shaft is turned about its axis to disalign its projections or keys 12 relative to the keyways in the hosel.

Of the several filling materials mentioned herein rubber is considered the best because of its shock absorbing qualities (and its torsional virtues) and its capacity to definitely hold the parts together.

In the manufacture of "wood" heads, I obtain certain benefits by eliminating the relatively long hosel section through which the shaft passes, and 20 make possible the use of smaller rough blocks from which the heads are turned, thus saving a material which is growing scarce (persimmon). In the assembly of clubs of the "wood" type, I introduce into the head, as in Fig. 9, a metal hosel member 8a of a form to preserve the locking and 25 assembly technique described herein. I first bore the wooden head for the metal member—the lower body of this member having been prepared for a gluing assembly by having vulcanized there- 30 to a rubberized fabric. I then "rough up" the fabric surface and coat with glue. I also apply a thin coating of glue to the walls of the "bore." The two parts are then dried under pressure. When a proper union has been achieved, I then 35 completely finish the head in its full lacquered form and store it ready for the shaft assembly as described. An alternate assembly would consist of a drive fit of the metal hosel member into the wood head and a transverse screw 8b or rivet 40 holding it in place.

An alternate method of assembly may be employed as shown in Figs. 4 to 8 by making the hosel member of substantially straight form having one or more keyways or grooves 13 cut or 45 pressed lengthwise therein, Fig. 4, and a screw-head member 14 of substantially the same diameter having a stem 15 screw threaded into its body, the screw head member having keyway slots 16a cut therein so that they may be registered 50 with the keyways in the hosel member as the shaft is fitted to the head. After jointure has been made, a suitable tool operated from the upper end of the shaft may be inserted to give the screwhead member a quarter turn by engaging, 55 for instance, a rib or kerf in said screwhead or the keyways thereof, thus moving the keyways out of registration and bringing the under surface of the screwhead member into frictional contact with the top 13a of the internal rib or key 60 13b (or the like) in the shaft member Fig. 4. The length of this rib member is predetermined to have the top of it substantially flush with the top of the hosel stem on which the screwhead member rides. It will be noted that the internal rib (or 65 the like), closely fitting into the keyways, prevents any rotary movement in the parts and as the screwhead member (nut) is turned and tightened, the parts are locked against lengthwise movement. To prevent loosening of the screwhead (nut) member under a sequence of vibrations, I may drive down into the shaft against the screwhead member a soft rubber cork 17 that will be compressed against the walls of the shaft and in frictional contact with the screwhead member. A drop or two of solder may be used,

or rubber cement or plastic. I do not limit myself to any precise technique to insure against movement of the screwhead member under vibratory forces.

I may use in this modification a slug of rubber which may be vulcanized to the screwhead and the adjacent parts of the joint as in the form first described. In both forms it will be noticed that the golf head has an internal hosel. In Fig. 1 this hosel is provided with a relatively small stem portion extending between and connecting a larger diameter top or head portion, and a large diameter base portion. In Fig. 4 the stem below the head or top of the hosel is reduced to the extent of providing a groove or grooves 13 therein.

Reverting to Fig. 1, I show a metal disk or plate member 18 bearing on the rubber slug R. This disk fits the larger diameter of the hollow shaft. The mandrel by which pressure is applied to the disk, and which mandrel is moved along and within the hollow shaft to exert pressure upon the disk 18 and upon the flowing rubber, is of a diameter to fit slidably within the lesser diameter of the hollow shaft, and therefore a space is left around the mandrel adjacent the point where said mandrel contacts with the metallic disk 18. This would allow the flowing rubber to extrude upward into said space.

The metal disk however receives the end thrust of the mandrel and holding close contact with the side walls of the shaft forces all the rubber (substantially) downward. The metallic disc 18 is vulcanized to the rubber to avoid working loose.

Vulcanizable rubber compounds may be mixed to flow and vulcanize in hot water (just under boiling say 180° to 200°). The nature of compounding is a matter of choice and routine to the skilled worker in the art. Some may prefer steam as a medium and the compound adjusted accordingly.

It will be noticed that the hosel at its large diameter base portion, near where it joins the head of the club, has an upwardly facing annular shoulder lying in one plane at a right angle to the axis of the hosel, and this shoulder acts as a stop to determine the position of the shaft when it is thrust into connection with the hosel. This limiting of the movement of the shaft which may be done also by the lower end of the key 12 Fig. 1 or 13b Fig. 4 coming against a shoulder on the hosel causes the upper end or shoulder on the key or keys 12 or 13b to assume such a level in respect to the head of the hosel that when the shaft is turned to interlock with the hosel by disaligning the key 12 in respect to the keyway 10a, the said upper end or shoulder of the key 12 will be close to the under face or shoulder 11 of the head of the hosel. Desirably no camming action takes place between the key and the downwardly facing shoulder 11 of the head of the hosel, but the upper end of the key will be substantially in contact with said shoulder 11 or near enough to prevent any appreciable movement between said parts in a direction lengthwise of the shaft. The small crevices between the parts will receive the rubber filling and upon being vulcanized will connect the shaft and hosel and prevent any substantial movement between said parts in addition to the cushioning action that said rubber or like filling material would provide. The same principle is involved in both forms of applicant's invention of providing a preformed gated head 10 in the form of Figs. 1, 2, 3 and 9 (or the gated head 14 of Figs. 4, 8), surmounting

a reduced neck portion 9 of Fig. 1 or 8a of Fig. 9 (or as reduced by grooves 13 in Fig. 4) and providing an under shoulder 11 of Fig. 1 to be immediately engaged by the key 12 Fig. 1 (or key 13b in the modification of Fig. 4 engaging under the shoulder of the head 14) desirably without any camming action. The shaft is stopped, as to lengthwise movement, in both modifications 1 and 4 as soon as the upper shoulder on the key gets into a plane permitting it to get under the shoulder 11 of Fig. 1 (or its equivalent in Fig. 4) by a relative rotative movement between the shaft and the head of the hosel, the shaft being the part that turns in Fig. 1. The screw head 14 is the part that turns in Fig. 4 to disalign its gateway with the key 13b (Fig. 4).

I claim:

1. A golf club head having an internal hosel member with a relatively large base and head portion, with a keyway in the exterior lateral face of the head extending from the top through the bottom of said head, and a relatively small waist or stem portion connecting the said base and head portion.
2. A golf club head having a hosel member, said hosel member having an enlarged top portion and a relatively small stem portion and a gateway, or keyway, in the top portion leading to the space around the small stem and below the enlarged top to accommodate passage of an interlocking key member to said space in a shaft assembly.
3. A golf club having a hosel, said hosel member having an enlarged top portion, a relatively small stem portion, one or more keyways in the top portion, a shaft member fitted over the hosel member, internally depressed key or locking means associated with the shaft member and engaging under the shoulder formed by the enlarged top portion of the hosel member, said shoulder being in one plane at right angles to the axis of the hosel, and a filler material introduced between the two parts to unify and solidify their union and for positioning the shaft with its key substantially located in said plane and in contact with said shoulder.
4. In a golf club a head having a hosel member of the internal type, said hosel having a space or spaces to accommodate an inwardly projecting part of the shaft wall to prevent rotary movement of one of said members relative to the other and means associated with the hosel member to produce endwise contact against the inwardly projecting part of the shaft wall to lock the parts against lengthwise movement or separation.
5. A golf club according to claim 4, having means to lock the means associated with the hosel member to prevent rotary movement thereof under vibration.
6. A golf club according to claim 4 in which said associated means has a keyway for the passage of the inwardly projecting part or key of the shaft when in alignment therewith, and is adapted to have relative rotary movement in respect to said key of the shaft when manually adjusted to disalign said key and keyway, and locking means in the form of a block of rubber or like material to hold said associated keyway carrier by pressure thereon.
7. A golf club of the internal hosel type having interengaging means between the hosel and the shaft, consisting of a key on the shaft, and a rotatable head on the hosel having a keyway, said keyway if aligned with the key on the shaft allowing lengthwise relative movement of the shaft

and hosel, said head being rotatable by means engaged therewith by insertion from the upper end of the shaft.

8. A golf club comprising a head having an internal hosel provided with a head portion, having a keyway extending in the external laterally facing surface of the head in a direction substantially lengthwise of said hosel, a hollow shaft having a key and adapted to be positioned on the hosel by a relative movement axially and then rotatively in a plane at right angles to the axis after said key has passed through the keyway, said key then having assumed a position against the underside of the hosel head, lying in a plane at right angles to the axis, and means for fixing the shaft in its said position with the key disaligned in respect to the keyway to lock the shaft to the hosel.

9. A golf club having a head with an internal hosel having a keyway or groove extending lengthwise thereof, a head for said hosel connected thereto to turn in relation thereto, said hosel head having a keyway to be aligned with or disaligned from the keyway of the main part of the hosel, a shaft having a key to pass through the keyway in the hosel head and into the keyway of the hosel, to hold the shaft against rotary movement relative to the hosel, the upper end of said key providing a shoulder and disposed adjacent the upper end of said keyway of the hosel, said turnable head having a downwardly facing shoulder to contact with the shaft key and having also means by which it may be turned by an instrument introduced into the hollow shaft from the top thereof, said turning of the head causing it to disalign its keyway from that of the hosel and to lock the key of the shaft by the shoulder of the hosel head contacting said shaft key, substantially as described.

10. A golf club having an internal hosel provided with a head rotatably connected thereto, a hollow shaft surrounding said hosel, said rotatable head having a shoulder to engage a complementary shoulder of the shaft to lock said shaft on the hosel, said head having means whereby it may be rotated to cause the shoulder thereof to overlie the shoulder on the shaft and thereby lock the shaft in place and means for holding the rotatable head in its locking position, substantially as described.

11. A golf club comprising a hollow metallic shaft, a club head having a hosel within said shaft, said hosel having an upwardly facing stop shoulder to be contacted by a part of the shaft to limit the lengthwise positioning of the shaft onto the hosel, said hosel having a head provided in its exterior laterally directed face with a keyway or keyways extending in a direction substantially vertical or lengthwise of said hosel from the top through the bottom of said hosel head, said hollow shaft having a key projecting into the interior thereof to pass through the said keyway with the upwardly facing upper end of the key disposed in a plane lying at right angles to the axis of said hosel and immediately adjoining and below the downwardly facing shoulder on the under side of said hosel head, which shoulder likewise lies in a plane at right angles to the hosel axis, said key of the shaft locking the said shaft and hosel head against separating movement when the shaft and hosel head are relatively set with the key disaligned from the keyway and engaging said downwardly facing shoulder, and means for retaining the shaft key and the keyway

in said disaligned relation, substantially as described.

12. A golf club according to claim 11 with the hosel head with its keyway rigidly fixed to the hosel.

13. A golf club according to claim 11 in which the head of the hosel is mounted substantially coaxially with said hosel and is rotatable relative to said hosel to disalign its keyway with the key of the shaft, substantially as described.

14. A golf club comprising a hollow metallic shaft, a club head having a hosel within said shaft, said hosel having an upwardly facing stop shoulder to be contacted by a part of the shaft to

15. limit the lengthwise positioning of the shaft onto the hosel, said hosel having a head provided in its exterior laterally directed face with a keyway or keyways extending in a direction substantially vertical or lengthwise of said hosel from the top

20. through the bottom of said hosel head, said hollow shaft having a key projecting into the interior thereof to pass through the said keyway with the upwardly facing upper end of the key disposed in a plane lying at right angles to the axis of said

25. hosel and immediately adjoining and below the downwardly facing shoulder on the under side of said hosel head, which shoulder likewise lies in a plane at right angles to the hosel axis, said key of the shaft and the downwardly facing shoulder

30. locking the said shaft and hosel head against separating movement when the shaft and hosel are relatively set with the key disaligned from the keyway, and means for retaining the shaft key and the keyway in disaligned relation, said

35. means consisting of filling material in the comparatively small space between the shaft and hosel for locking said parts against movement from the disaligned positions of the shaft key and the keyway.

40. 15. A golf club comprising a tubular shaft and an internal hosel received within said tubular shaft, said hosel having a head with a longitudinally disposed gate or keyway therein, said hosel below said head being reduced providing a space

45. between the body of the hosel at the reduced portion and the internal surface of the tubular shaft, said shaft having a key thereof projecting inwardly of the internal surface of the shaft and disposed in said space, said gate or keyway of the

50. said hosel head permitting passage of said key of the shaft longitudinally therethrough and into said space between the reduced portion of the hosel and the internal surface of the shaft, said keyway permitting passage of filler material therethrough to the spaces between the shaft and hosel, and filler material in said spaces, said filler material being set and holding the parts in position.

60. 16. A golf club according to claim 15 in which said hosel head and shaft key have shoulders interlocked by relative rotary movement between the shaft and hosel head.

65. 17. A golf club comprising a club head having a hosel of the internal type, said hosel having a base portion connected with the club head, and said hosel having a head portion connected with said base portion by a stem of reduced diameter leaving a shoulder at the under side of said hosel head and another shoulder at the upper side of said base portion, said hosel head having a keyway or keyways extending lengthwise thereof, a hollow shaft extending over and enclosing the internal hosel and having a key portion on its inner side adapted to pass through the keyway of

the hosel and to lie when turned substantially against the shoulder on the lower face of the hosel head, said shaft at its lower end fitting against the shoulder at the upper part of the base of the hosel, and being stopped thereby in a predetermined lengthwise position, and means for holding the shaft against turning relative to the keyway of the hosel head to thereby maintain the shaft in locking engagement with the hosel by reason of the disalignment of the key portion of the shaft with the keyway of the hosel head, the said means for locking the shaft and the internal hosel together against relative circumferential movement consisting of filling material entered in the spaces in the joint between the shaft and the internal hosel.

18. A golf club according to claim 17 in which the said filling material in the joint between the hollow shaft and the internal hosel is rubber or similar material vulcanized to the parts with which it contacts to hold them against assuming such relative positions rotatively as would aid their separation while allowing yielding action in the joint, substantially as described.

19. A golf club comprising hosel and shaft members having interlocking shoulders, the shoulder of the hosel facing downwardly and having a longitudinal keyway therethrough for the flow of filler material to the spaces between the shaft and said hosel, said shaft having a projection providing said shoulder on the shaft, said longitudinal keyway providing passage for the projecting shoulder on the shaft to pass therethrough into its position engaged under and interlocked with the shoulder on the hosel by relative turning movement, and filling material in the spaces between the shaft and hosel, said filling material being set and holding the parts in interlocked position, substantially as described.

20. A golf club comprising a tubular shaft, and a hosel or stem of the golf club head received within the lower end of said tubular shaft, said

shaft having a projection thereon providing an upwardly facing shoulder, said hosel having a head providing a downwardly facing shoulder, said hosel head having a longitudinal keyway therein affording passage for said shaft projection longitudinally through said hosel head, and affording passage for filling material through said head into the spaces between the shaft and hosel, said upwardly facing shoulder of said shaft projection engaging under said downwardly facing shoulder of said hosel head in interlocking relation preventing longitudinal separation of the hosel and shaft, said interlocking engagement of the said shoulders being at a point rotatively removed from said longitudinal keyway of said hosel head, and filling material in said keyway and in the spaces between the shaft and hosel and holding the parts in interlocked position.

21. A golf club comprising a tubular shaft and an internal hosel received within said tubular shaft, said hosel having a longitudinally disposed keyway therein, said shaft having a key thereof projecting inwardly of the internal surface of the shaft and designed to be received in said keyway in the hosel, said keyway permitting passage of filler material thereinto, and filler material in said keyway and around the key, said filler material being set and holding the parts in position, the upper end of the keyway in said hosel being closed by a plate member secured to the upper terminal portion of said hosel.

22. A golf club comprising a tubular shaft and an internal hosel received within said tubular shaft, binding material between the surfaces of the shaft and internal hosel unifying the shaft and hosel, and a plate member secured to the upper end of the internal hosel and overlying and engaging the said binding material to prevent the binding material from moving upward beyond the said plate member.

MILTON B. REACH.
